 The M. W. Kellogg Company, Jersey City, N. J.,
 a corporation of Delaware

Application March 30, 1948, Serial No. 17,891

8 Claims. (Cl. 139—281)

1

The present invention relates to a new and improved connector rod between the filling feeler slide mechanism of a fly shuttle loom.

In a conventional loom the operation of the transferring or replenishing mechanism is initiated by the rotation of a starting rod. A feeler controlled slide mechanism has a filling cam follower, provided with a trip, which through filling motion cam is brought forward each time the shuttle is checked in the left-hand side of the loom. A feeler slide located between the filling cam follower and the starting rod is ordinarily held in a position that does not engage the trip. A feeler mechanism operates to detect substantial exhaustion of the filling supply in the bobbin and when this condition is indicated, a filling feeler connector rod is put into action to cause the feeler slide to engage said trip, so that said slide is moved into position to rotate the starting rod and thereby initiate operation of the replenishing mechanism. The feeler mechanism comprises a spring-pressed feeler indicator arm mounted for pivotal movement and carrying a feeler tip which comes into engagement with the bobbin during the beat-up movement of the lay. So long as the feeler tip engages yarn on the bobbin, it is restrained against indicating movement by the comparatively soft mass of yarn. When the bobbin is nearing exhaustion and the feeler tip finds a bare portion of the bobbin during beat-up movement, said tip slips on the denuded portion of the bobbin, thereby tilting the feeler indicator arm into actuating engagement with one end of the filling feeler connector rod causing said rod to move endwise against the action of a spring. The endwise movement of the connector rod locks the slide to the trip to cause the movement of the filling feeler slide to rotate the starting rod upon the next forward stroke of the trip.

The filling feeler connector rod must be adjusted in length for correct timing of operation of the filling feeler slide. Also, it is important that the end of the filling feeler connector rod nearest the filling feeler indicator arm be maintained at a proper clearance distance from said arm in inoperative position of said arm, to assure proper indications upon absence of filling and to assure against false indications.

One object of the present invention is to provide a new and improved filling feeler connector rod constructed to permit its easy lengthwise adjustment and at the same time to maintain a predetermined clearance distance between the feeler end of said rod and the indicator feeler

arm when said arm is in non-indicating position.

In carrying out certain features of the present invention, the filling feeler connector rod has a length adjusting loop near its feeler end. The end section of the loop nearest its feeler end is offset from the adjoining end section and is pressed by the action of a spring into engagement with the frame or case mounting the feeler indicator arm. The end feeler section of the connector rod passes through a wall of the feeler frame or case, so that the feeler end of said connector rod is in the path of indicating movement of the feeler indicator arm. This arrangement serves to predetermine the position of the feeler end of the connector rod with respect to the feeler indicator arm and since adjustments in the length of the connector rod are made by pulling or pushing at the ends of the loop, said feeler rod end will always remain at a constant distance from the wall engaging end section of the loop regardless of any adjustments in said loop. The proper distance between the feeler rod end and the feeler indicator arm will therefore be assured for all adjustments of rod length.

Various other objects, features and advantages of the invention will be apparent from the following particular description and from an inspection of the accompanying drawings, in which—

Fig. 1 is a top front perspective of the left-hand side of the loom showing a portion of the filling feeler mechanism, a portion of the filling feeler slide mechanism and the connector rod embodying the present invention disposed between the two mechanisms;

Fig. 2 is a perspective view of the connector rod;

Fig. 3 is a fragmentary perspective of portion of the filling feeler mechanism in non-indicating position and the end portion of the connector rod associated therewith;

Fig. 4 is a fragmentary perspective of portion of the filling feeler slide mechanism and the end portion of the connector rod associated therewith and shows said rod in non-indicating position;

Fig. 5 is a perspective similar to that shown in Fig. 4 except that the connector rod is shown moved endwise by the feeler mechanism in position to cause the slide to move forward on the next forward stroke of the filling cam follower.

The loom to which the filling feeler connection rod of the present invention may be applied may be of the general standard type and may com-

prise a conventional feeler mechanism in which a feeler tip is moved sidewise along the bare portion of a nearly exhausted bobbin to actuate a feeler connector rod or may comprise the improved feeler mechanism 10 as shown, forming the subject matter of a copending application Serial No. 708,638, filed November 8, 1946, now Patent No. 2,445,695. The improved feeler mechanism 10 comprises generally a spring-pressed feeler rod 11 mounted for endwise movement in a fixed frame or case 12 and pivotally carrying a feeler tip 13 presenting a curved feeler surface 14. A spring-pressed indicator arm 15 pivotally secured to the feeler tip 13 is mounted for endwise and angular movement in the case 12. A feeler connector rod 17 mounted for endwise movement has its feeler end in the angular path of movement of the indicator arm 15.

The feeler mechanism 10 is mounted on one side of the loom, as for example, on the left side and in front of the picking course of the shuttle. Upon each forward beat-up movement of the lay, the checked bobbin engages the feeler tip 13. When the bobbin has an ample supply of filling yarn, the yarn provides enough friction to prevent rotation of the tip 13 about its pivotal mounting so that the indicator arm 15 is moved endwise by the advancing bobbin without actuating the connector rod 17.

When the supply of yarn on the bobbin is nearly exhausted, and a bare portion of the bobbin engages the feeler tip 13 on the beat-up stroke of the lay, the feeler tip 13 rotates about its pivotal mounting to cause the indicator arm 15 to tilt angularly into engagement with one end of the connector rod 17, to move said rod endwise against the action of a spring 20 at its other end. At said other end, the connector rod 17 operates a filling feeler slide mechanism 21 to initiate the operation of the replenishing mechanism.

The filling feeler slide mechanism 21 may be of the standard type or may be of the improved type shown herein and described more fully in copending application Serial No. 706,826, filed October 31, 1946, now Patent No. 2,443,401. In this improved feeler slide mechanism, there is provided the usual starting rod (not shown) which upon rotation, initiates the operation of the replenishing mechanism in a manner well known in the art. For rotating this starting rod, there is rigidly connected thereto a crank arm (not shown) having at its outer end a knuckle joint connection to one end of a short rod, the other end being secured to the forward end of a filling feeler slide 22. The slide 22 is guided for horizontal movement forwardly and rearwardly along a bed plate 23, mounted on frame plates 24 constituting the left loomside, and is maintained in inoperative forward position by a spring (not shown) acting on the starting rod, and by a stop (not shown) for said rod operating against the force of said spring in a manner well-known in the art.

A filling cam follower (not shown) is provided which may be oscillated by virtue of the filling motion cam on the main cam shaft (not shown) in the usual manner and which is brought forwardly each time that the shuttle is checked on the left-hand side of the loom. The cam follower terminates at its outer end in a dog extending in an elongated slot 30 in the feeler slide 22 and movable in said slot. Between the cam follower dog and the slide 22 is a latch which is ordinarily released to permit said dog to operate idly in the slot and which is automatically tripped by the

connector rod 17 to lock said slide to said dog and thereby cause the forward movement of the slide in a direction to rotate the starting rod upon the next forward movement of the cam follower dog. The latch comprises a plunger or slide bolt (not shown) having a slide fit in a bore 31 in the slide 22 and connected to the cam follower dog.

As the cam follower is oscillated, the latch bolt is moved idly thereby in the slide 22. To latch the bolt to the slide 22 upon actuation of the connector rod 17, there is provided a trip plunger 32 and a ball catch piece (not shown) in said slide between said trip plunger and said bolt. The ball catch piece is normally inactive in the position of the connector rod 17 shown in Fig. 4, to permit the idle movement of the bolt in the slide 22 and is adapted to be cammed by the trip plunger 32 into position to lock said bolt to said slide, when said trip plunger is moved against the action of the spring 20 by the connector rod 17, upon detection of absence of filling, as shown in Fig. 5.

The trip plunger 32 has a head 33 with an apertured lug 34 to which one end of the connector rod 17 is anchored by means of a hock connection 35. The spring 20 encircling the trip plunger 32 bears at one end against the outside of the slide 22 and at the other end against the head 33 to maintain the trip plunger normally in unlatching position and to urge the connector rod 17 towards the filler indicator arm 15.

As an important feature of the present invention, the connector rod 17 is constructed to permit its easy lengthwise adjustment, while maintaining the feeler end of said rod at a predetermined constant distance with respect to the feeler indicator arm 15. To that end, the connector rod 17 is made of stiff though bendable metal wire, such as brass, and the end section of said rod nearest the feeler mechanism has a loop 40 desirably in the form of a circular coil consisting of about one and one-half convolutions, so that the rod sections 41 and 42 beyond the ends of said loop extend in substantial alignment diametrically of said loop. The end section 43 of the loop 40 nearest the feeler end of the connector rod 17, being substantially right-angularly offset from the feeler end section 41 of said rod, engages the side wall 45 of the feeler case 12 in inoperative position of said rod, while said feeler end section 41 extends through said case wall 45 with a slide fit and rests on a shelf 46 at the rear end of said case.

While there are no feeler indications, the coil spring 20 presses the connector rod 17 lengthwise and causes thereby the offset end loop section 42 to abut the side case wall 45 as shown in Fig. 3. In this limiting position, the feeler end of the connector rod 17 will be spaced the required distance from the indicator arm 15. Any vibrations of the inactive indicator arm 15 will, therefore, not be transmitted to the feeler end of the connector rod 17. The clearance between the feeler end of the connector rod 17 and the indicator arm 15 is, however, small enough so that angular indicating movements of said indicator arm will be almost immediately transmitted to the connector rod 17.

The length of the connector rod 17 can be easily adjusted by merely pulling or pushing on the rod sections 41 and 42, according to whether it is desired to shorten or lengthen said rod, to cause expansion or contraction of the loop 40 therebetween. This loop straining action will cause a corresponding change in the overall length of the connector rod 17 without changing

the length of the feeler end connector section 41. Therefore, regardless of any adjustments in the length of connector rod 17, the outer feeler end of the connector rod in inoperative position of said connector rod, will always be at a fixed distance from the indicator arm 15.

It should be noted that the connector rod of the present invention may easily replace the conventional connector rod in existing looms.

While the invention has been described with particular reference to a specific embodiment, it is to be understood it is not to be limited thereto but is to be construed broadly and restricted solely by the scope of the appended claims.

What is claimed is:

1. In a loom having a filling feeler mechanism with a frame structure and a filling feeler slide mechanism, a connector rod for transmitting indications from said feeler mechanism to said slide mechanism, said connector rod having a loop near its feeler end to permit said rod to be adjusted lengthwise by a straining of said loop, the end section of said loop nearest said feeler rod end being offset from the adjoining end section of said rod for stop engagement with said frame structure in inoperative position of said connector rod, whereby the position of said feeler rod end with respect to the rod actuating part of said feeler mechanism is fixed, irrespective of adjustments in the length of said rod.

2. In a loom, a connector rod as described in claim 1, said loop being in the form of a coil having approximately one and one-half substantially circular convolutions, so that the sections of said rod beyond the ends of said loop are disposed substantially in alignment diametrically of said loop.

3. In a loom, a connector rod as described in claim 1, said loop being in the form of a coil having one or more substantially circular convolutions, the sections of said rod beyond the ends of said loop being disposed substantially in alignment diametrically of said loop.

4. In a loom having a filling feeler mechanism with a frame case and a filling feeler slide mechanism, a connector rod for transmitting indications from said feeler mechanism to said slide mechanism, spring-pressed endwise towards said feeler mechanism and having a loop near its feeler end to permit said rod to be adjusted lengthwise by expansion or contraction of said loop, the end section of said loop nearest said feeler rod end being offset from the adjoining feeler end section of said rod for stop spring-pressed engagement with a side wall of said frame case in inoperative position of said connector rod, whereby the position of said feeler rod end with respect to the rod actuating part of said feeler mechanism is fixed, irrespective of adjustments in the length of said rod.

5. In a loom having a filling feeler mechanism with a frame case and a filling feeler slide mechanism, a connector rod for transmitting indications from said feeler mechanism to said slide mechanism, spring-pressed endwise towards said feeler mechanism and having a coil near its feeler end with approximately one and one-half substantially circular convolutions, so that the sections of said rod beyond the ends of said coil are disposed substantially in alignment diametrically of said coil, said coil permitting said rod to be adjusted lengthwise by expansion or contraction of said coil, the offset end section of said coil nearest said feeler rod end being spring-pressed against a side wall of said frame case in inoperative position of said connector rod, whereby the position of said feeler rod end with respect to the rod actuating part of said feeler mechanism is fixed irrespective of adjustments in the length of said rod.

6. As a new article of manufacture, a filling feeler connector rod for a loom, having a length adjusting loop near the feeler end, the end section of said loop near said feeler end being offset from the adjoining feeler end section of said rod to engage a fixed frame part of the feeler mechanism of the loom in inoperative position of said connector rod and to position thereby the feeler end of said rod at a fixed constant distance from the connector rod actuating part of said feeler mechanism, the other end of said rod having means for attachment to a latching part of a filling feeler slide mechanism.

7. As a new article of manufacture, a filling feeler connector rod for a loom, as described in claim 6, said loop being in the form of a coil having approximately one and one-half substantially circular convolutions so that the sections of said rod beyond the ends of said loop are disposed substantially in alignment diametrically of said loop.

8. As a new article of manufacture, a filling feeler connector rod for a loom as described in claim 6, said loop being in the form of a coil having one or more substantially circular convolutions, the sections of said rod beyond the ends of said loop being disposed substantially in alignment diametrically of said loop.
